Primary Examiner — Kevin K Rudzinski*Assistant Examiner* — Richard E Yenchesky(74) *Attorney, Agent, or Firm* — Panitch Schwarze Belisario & Nadel LLP(57) **CLAIM**

The ornamental design for a vacuum attachment, as shown and described.

DESCRIPTION

FIG. 1 is a front and right-side perspective view of a vacuum attachment in accordance with my new design;

FIG. 2 is a right-side elevational view thereof;

FIG. 3 is a left-side elevational view thereof;

FIG. 4 is a front elevational view thereof;

FIG. 5 is a bottom plan view thereof; and,

FIG. 6 is a top plan view thereof.

Any portions of the vacuum attachment potentially not shown in the drawings or described in the specification form no part of the claimed design.

1 Claim, 5 Drawing Sheets(56)
